RECOVERY OF TAR ACIDS

Stuart Parmelee Miller, Englewood, N. J., assignor to The Barrett Company, New York, N. Y., a corporation of New Jersey

Application April 19, 1930. Serial No. 445,617

9 Claims. (Cl. 202—67)

This invention relates to improvements in the recovery of tar acids as a by-product of the operation of coal carbonization plants such as coke oven batteries or gas retort plants or low temperature carbonization plants with the simultaneous production of a bituminous residue which may be a low melting point pitch. It includes the bituminous residue or pitch as a new product. The tar acids may be recovered as such, or as a tar acid oil.

The invention will be particularly described with respect to coke ovens of the by-product type.

In the ordinary operation of the common types of coke oven batteries, the coal distillation gases from the individual ovens are collected in a gas collector main where they are partially cooled, and from there they pass to condensers where they are further cooled. A heavy tar is separated from the gases by the partial cooling of the gases in the collector main and such scrubbing of the gases as is incident to the collector main operation. A light tar or tarry oil is separated from the resulting gases in the condensers. The heavy tar and light tar or tarry oil fractions are ordinarily blended together and the resulting total tar is distilled or burned as fuel or is otherwise disposed of.

According to this invention, the various tar fractions recovered from the coke oven gases are not blended but at least one fraction is separately recovered and treated for the removal of tar acids and the production of a low melting point pitch. According to a preferred method of carrying out the invention, two separate tar fractions are recovered from the coke oven gases, namely a heavy tar from the collector main and a tarry oil from the condensers. The tarry oil is then treated for its tar acid content and a bituminous residue is produced, which may be a low melting point pitch or a thinner, more fluid material.

Coke oven gases vary in composition, depending upon the kind of coal treated and the temperature of the distillation. The tar produced varies accordingly and moreover the tar fractions vary, depending upon the extent to which the gases are cooled in the collector main, etc. The most widely used commercial types of tar acids have boiling points within the range between about 100 and 230° C. The tar which separates in the collector main of a coke oven battery contains a smaller percentage of tar acids than the tarry oil from the condensers.

According to a preferred method of carrying

out this invention, the cooling in the collector main is regulated to permit as large a portion as possible of the tar acids to pass over into the condensers and thus produce a tarry oil of relatively high tar acid content, as compared with the total tar or with the heavier tar from the collector main.

As one example of tar acid distribution in such tar fractions it was found that the tarry oil from the condensers of an ordinary coke oven battery contained a large percentage (about fifty or more percent) of oils boiling within a narrow temperature range, (between 210 and 220° C. vapor temperature) and that the oils of this boiling range were high in tar acids. On the other hand, neither the heavier tar separating in the collector main nor the total tar produced if all tar fractions were collected together as is the usual practice contained such large percentages of narrow boiling range oils; the boiling point of oils from such tars (to, say, pitch of 105° F. melting point) rose quite rapidly during the early portions of a test distillation and again after thirty or forty percent of oils were distilled.

The amount of oils boiling near the tar acid range contained in total tar, or in tarry oils separated and treated as in this process, will vary with the composition and conditions of production of the tar. The tar acid oil fraction accompanying the tar acids, when these are recovered by distillation, may therefore vary considerably from the example given. In all cases, however, tarry oils may be recovered and worked up as described which have a higher tar acid content than the total tars of which they are respectively fractions. The distillation of the tarry oils from the condensers is preferably so controlled that although the lower boiling tar acids are volatilized, the major portion of the less valuable higher boiling acids is left in the pitch residue.

Tar acids can be recovered from the tarry oils from the condensers more efficiently than from total tar or from the heavy tar from the collector main because of the relatively greater percentage of tar acids contained in the tarry oils. The residue which remains after volatilization of the tar acids is a low melting pitch suitable for industrial use, e.g. for fuel. The tar acid oils may be distilled from the tarry oils in any suitable type of still. The distillate may be extracted with caustic or other alkaline reagent to recover the tar acids and the resulting neutral oil. The neutral oils may be blended with the

distillation residue to form a product suitable for fuel.

According to a preferred method of carrying out the invention in connection with a by-product coke oven plant, the tarry oils are distilled by being brought into direct contact with hot coal distillation gases from selected ovens of the plant, in the form of a fine intense spray, as more fully described in application Serial 5 No. 326,771, filed December 18, 1928 or application Serial No. 326,769, filed December 18, 1928. The tarry oils may be distilled in steam or other hot gases or in an ordinary tar still or by any other suitable means. Preferably the tar acids 10 are volatilized from the tar without substantial decomposition of any of the constituents of the tar, and if the neutral oils remaining after extraction of tar acids from the distillate are returned to the distillation residue, the resulting 15 product is of substantially the same composition as the original tarry oils except for the absence of the tar acids. It is a dephenolized or partially dephenolized tarry oil.

In the accompanying drawing, three curves 20 A, B and C are shown by way of example, which are test distillation curves of distillate oils from tars from a Semet-Solvay coke oven battery and are representative in a general way of distillates from the total tar, heavy tar and tarry oil, 25 respectively. It is to be noted that the distillate from the tarry oil from the condensers after being heated to a temperature of 205 or 210° C., shows little additional rise in temperature until about 75% of the oil has been distilled off. 30 Neither the distillate from the total tar, i. e. the blend of the tarry oil and heavy tar, nor from the heavy tar, shows on distillation any such gradual rise in temperature over a prolonged period of time. A large percentage of the oil 35 may be distilled from this tarry oil without producing a high melting point pitch. The distillation of the tarry oil can be controlled so as to produce a distillate of high tar acid content and yet yield a pitch of low melting point, for example, a pitch with a melting point between 100 and 110° F.

The tar acids may readily be extracted from the distillate and the remaining neutral oils may be blended with creosote oil or be otherwise disposed of. According to one method of carrying 40 out the invention, these neutral oils are blended with the distillation residue to produce a product suitable for fuel. This is particularly advantageous at plants producing large amounts of 45 tar and having a large demand for liquid fuel, e. g. coke plants connected with steel plants.

The distribution of the tar acids in the tar obtained from coke oven gases is indicated in a general way in the following example, although it is to be understood that the percent of tar acids present in the tar and the composition of the tar vary with the kind of coal coked and the temperature of coking, etc. In general the higher the coking temperature the lower the tar 55 acid content, although the tar acid content depends to large extent upon the kind of coal being coked, the speed of coking, the design of the ovens, etc.

As a further example of my invention, 65% 60 of the tar from a coke oven battery may be recovered as heavy tar in the collector main and the remaining 35% recovered as a tarry oil fraction in the condensers containing usually about 50% of the total acids present in the 65 total tar. If in such a case the tar acids repre-

sent 3% of the total tar, the tarry oil will have a tar acid content of about 4.3% and the heavy tar will have a tar acid content of only about 2.3%. If the tarry oil is distilled to pitch with a melting point of about 105° F., and 35% of 80 distillate is obtained, this will ordinarily contain about 75% of the acids present in the tarry oil. This distillate will constitute about 12.25% by volume of the total tar and will contain about 1.125 parts by volume of tar acid per 100 parts of the total tar recovered. It will have a tar acid content of about 9.2%. The distillate from the tarry oil would have the following analysis:

10% crude coal tar light oils	90
9% tar acids	
61% crude naphthalene	85
20% creosote oil	

The tar acids can be recovered from this distillate in any suitable manner as by extraction with caustic soda to produce carbolate and the acids can then be regenerated from the carbamate by acidification with carbon dioxide, sulfuric or other acids.

As another example may be taken a tar produced from a Koppers battery. The total tar had a tar acid content of 2.3%. By separately collecting the heavy tar deposited in the collector main and the tarry oils condensed in the condensers, however, the latter were obtained with a tar acid content of 5.4%. By distilling this tarry oil fraction, (say, 18-25% of the total tar) it was possible to obtain an oil 105 rich in tar acids and well suited to the usual tar acid extraction with caustic soda. It was thus possible to obtain a substantial yield of tar acids economically by this method with the distillation of only a relatively small portion of the tar, (e. g. $\frac{1}{5}$ to $\frac{1}{3}$) from tars of low 110 tar acid content, from which the recovery of tar acids by the usual process would often be uneconomical.

While the advantages of the method are not restricted to tars of low tar acid content in 120 the total tar, they are especially marked when the total tar has a content of 3% or less of tar acids.

The pitch remaining after tar acid oils have been volatilized from the tarry oils with or 125 without the neutral oils of the same boiling range as the tar acids, may be blended with the heavy tar from the collector main or with tarry oil from the condensers or other tar for use as fuel, although stripped tar or the de- 130 phenolized tar remaining after the removal of tar acids from the tarry oils is suitable for use as fuel directly.

In general, the method of this invention permits recovery of a given amount of tar acids 135 from a given tar with distillation or treatment of much less tar than the usual method, and (if the oil is extracted with caustic soda) with the extraction of much less oil.

Furthermore, the tar acids so recovered, or 140 contained in the oils so recovered, are of a lower and more desirable boiling range than those recovered from a corresponding total tar by the usual methods.

I claim:

1. The improved method of recovering coal tar acids, which comprises fractionally cooling the coal distillation gases from a coal carbonization plant so as to recover a heavy tar relatively low in coal tar acids and a tar oil of 145

relatively high coal tar acid content, and separately recovering the coal tar acids from the tar oil.

2. The improved method of recovering coal tar acids, which comprises cooling the coal distillation gases from a coal carbonization plant so as to recover a heavy tar relatively low in coal tar acids and a tarry oil of relatively high coal tar acid content, and separately treating the tarry oil to recover the coal tar acids therefrom and produce a bituminous residue low in coal tar acids.

3. The improved method of recovering coal tar acid oils, which comprises partially cooling coal distillation gases in the collector main of a coke oven battery and separating heavy tar from the gases therein, further cooling the gases in condensers to produce a tarry oil, separately collecting the tarry oil and separately distilling it to produce a distillate of high coal tar acid content and a low melting point coal-tar pitch suitable for fuel.

4. The improved method of recovering coal tar acids, which comprises partially cooling coal distillation gases in the collector main of a coke oven battery and separating heavy tar from the gases therein, further cooling the gases in condensers to produce a tarry oil, separately collecting the tarry oil, separately distilling it to produce distillate of high coal tar acid content and a low melting point coal-tar pitch suitable for fuel, and extracting coal tar acids from the distillate.

5. The improved method of recovering coal tar acid oils, which comprises fractionally condensing the coal distillation gases from a coal carbonization plant to produce a tarry oil which on distillation yields at least 50% of distillate between 210 and 220° C., and distilling the tarry oil to produce separately distillate of high coal

tar acid content and low melting point coal-tar pitch suitable for fuel.

6. The improved method of producing a low melting point coal-tar pitch suitable for fuel at a coal carbonization plant, which comprises partially cooling the coal distillation gases in the gas collector main so as to separate a heavy tar, further cooling the gases in the condensers to produce a tarry oil and separately distilling the tarry oil to produce a coal-tar pitch with a melting point in the neighborhood of 105° F. tar acids, which comprises partially cooling coal tar acids, which comprises partially cooling coal distillation gases in the collector main of a coke oven battery to separate a heavy tar therefrom, further cooling the gases in the condensers to produce a tarry oil and separately distilling the tarry oil to volatilize coal tar acids and leave a distillation residue, extracting coal tar acids from the distillate so as to produce a neutral oil and blending the neutral oil with the distillation residue to produce a fuel pitch.

8. The method of treating coal distillation gases, the total tar from which has a tar acid content less than 3%, which comprises fractionally cooling the gases so as to produce a heavy tar fraction and a tarry oil fraction with a coal tar acid content greater than 3%, separately distilling the tarry oil fraction and extracting the coal tar acids from the distillate.

9. The improved method of recovering coal tar acids from the coal distillation gases of a coal distillation plant which comprises partially cooling the gases so as to recover a heavy tar comprising about 65% of the total tar constituents of the gases, further cooling the gases to condense a tarry oil comprising about 35% of the total tar constituents originally present in the gases, and separately treating the tarry oil to recover coal tar acids therefrom.

relatively high coal tar acid content, and separately recovering the coal tar acids from the tar oil.

2. The improved method of recovering coal tar acids, which comprises cooling the coal distillation gases from a coal carbonization plant so as to recover a heavy tar relatively low in coal tar acids and a tarry oil of relatively high coal tar acid content, and separately treating the tarry oil to recover the coal tar acids therefrom and produce a bituminous residue low in coal tar acids.

3. The improved method of recovering coal tar acid oils, which comprises partially cooling coal distillation gases in the collector main of a coke oven battery and separating heavy tar from the gases therein, further cooling the gases in condensers to produce a tarry oil, separately collecting the tarry oil and separately distilling it to produce a distillate of high coal tar acid content and a low melting point coal-tar pitch suitable for fuel.

4. The improved method of recovering coal tar acids, which comprises partially cooling coal distillation gases in the collector main of a coke oven battery and separating heavy tar from the gases therein, further cooling the gases in condensers to produce a tarry oil, separately collecting the tarry oil, separately distilling it to produce distillate of high coal tar acid content and a low melting point coal-tar pitch suitable for fuel, and extracting coal tar acids from the distillate.

5. The improved method of recovering coal tar acid oils, which comprises fractionally condensing the coal distillation gases from a coal carbonization plant to produce a tarry oil which on distillation yields at least 50% of distillate between 210 and 220° C., and distilling the tarry oil to produce separately distillate of high coal

tar acid content and low melting point coal-tar pitch suitable for fuel.

6. The improved method of producing a low melting point coal-tar pitch suitable for fuel at a coal carbonization plant, which comprises partially cooling the coal distillation gases in the gas collector main so as to separate a heavy tar, further cooling the gases in the condensers to produce a tarry oil and separately distilling the tarry oil to produce a coal-tar pitch with a melting point in the neighborhood of 105° F. tar acids, which comprises partially cooling coal tar acids, which comprises partially cooling coal distillation gases in the collector main of a coke oven battery to separate a heavy tar therefrom, further cooling the gases in the condensers to produce a tarry oil and separately distilling the tarry oil to volatilize coal tar acids and leave a distillation residue, extracting coal tar acids from the distillate so as to produce a neutral oil and blending the neutral oil with the distillation residue to produce a fuel pitch.

8. The method of treating coal distillation gases, the total tar from which has a tar acid content less than 3%, which comprises fractionally cooling the gases so as to produce a heavy tar fraction and a tarry oil fraction with a coal tar acid content greater than 3%, separately distilling the tarry oil fraction and extracting the coal tar acids from the distillate.

9. The improved method of recovering coal tar acids from the coal distillation gases of a coal distillation plant which comprises partially cooling the gases so as to recover a heavy tar comprising about 65% of the total tar constituents of the gases, further cooling the gases to condense a tarry oil comprising about 35% of the total tar constituents originally present in the gases, and separately treating the tarry oil to recover coal tar acids therefrom.
